Primary Examiner — Keli L Hill(74) *Attorney, Agent, or Firm* — Sughrue Mion, PLLC(57) **CLAIM**

The ornamental design for an audio equipment, as shown and described.

DESCRIPTION

FIG. 1 is a perspective view of the front, top and right side of an audio equipment showing my new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof; and,

FIG. 8 is an enlarged view at a portion indicated by 8 in FIG.

1.

The broken line showing of the audio equipment is included for the purpose of illustrating portions of the audio equipment and forms no part of the claimed design.
